CONTROL CIRCUITS

Murray G. Crosby, Riverhead, N. Y., assignor to
 Radio Corporation of America, a corporation
 of Delaware

Application March 14, 1942, Serial No. 434,743

15 Claims. (Cl. 179—171.5)

This application concerns timing modulation systems and has as its main object provision of a new and improved circuit for applying the potentials, characteristic of drifts in the main generator frequency and/or of wave length modulations on the generated wave and/or of non-symmetrical peak swings of the modulating potentials to the reactance tube in a wave length modulation system of the type disclosed in my United States application, Ser. No. 136,578, filed April 13, 1937, Patent #2,279,659, dated April 14, 1942.

My invention is applicable to frequency modulation systems, phase modulation systems, and systems having the characteristics of either or both. In the description and claims the terms "frequency modulation" and "wave length modulation" are intended to denote phase and frequency modulation, and phase or frequency modulation.

In describing my invention in detail reference will be made to the attached drawings wherein:

Fig. 1 illustrates a wave length modulator of the type involved here and is used to illustrate the purpose of and need for my present improved control potential translating circuit, and one embodiment thereof. This figure is similar in some respects to Fig. 1 of my U. S. application, Ser. No. 136,578, Patent #2,279,659.

Fig. 2 shows another embodiment of improved wave length modulators of this type, arranged in accordance with my present invention. An improvement in each of these modulators resides in the circuits coupling the wave frequency discriminator circuits and detector to the reactance tube for control purposes. This figure is similar in other respects to Fig. 2 of my above mentioned application.

In referring to Fig. 1 of the drawings, 10 is an oscillation generator having its grid 9 and anode 11 regeneratively coupled to a tank circuit 13. The generated oscillations modulated in length, as will be described hereinafter, are fed by winding 15, and/or amplitude limiter, and/or frequency multipliers in unit 5 for transmission from aerial 6. The tank circuit 13 is grounded at one end as shown and is shunted by the space between the cathode 25 and anode 33 of reactance tube 20. The anode 11 is also coupled by a phase shifting network C and R to grid 31 of the reactance tube by the coupling and blocking condenser CB. The network, etc., is such that a phase quadrature relation is maintained between the voltages on the grid 31 and the anode 33 so that current within the tube reaching the

anode is out of phase with the anode voltage about 90° to provide the reactive effect in shunt with the tank circuit 13, used for modulation purposes in these circuits.

5 The reactance provided by tube 20 is controlled at signal frequency by controlling the tube conductance and this is done by the application of modulating potentials to jack 35 and by way of transformer 29 and grid resistor 28 to the control grid 31. In modulation which is predominantly phase modulation the modulation potentials supplied to the jack 35 are modified in unit 39 substantially inversely in accordance with their frequency.

15 In order to stabilize the mean frequency of the generated oscillations and/or if desired to provide degeneration, wave energy modulated in wave length is supplied by lead 36 to the grid 38 of a combined oscillation generator and mixer tube 40. In this tube oscillations of substantially constant frequency are generated by means of electrodes 41 and 43, tank circuit 44, and piezoelectric crystal 45. These oscillations of substantially fixed frequency are mixed in the tube 20 with modulated waves from 13 and the beat frequency energy appears on anode 45 due to the electron coupling in the tube and are set up in the anode circuit 47. The anode circuit 47 is inductively coupled to the tuned circuit 50 connected to the anodes of the rectifiers 60 and 61 and is also coupled by a condenser 51 to the anodes of the rectifiers 60 and 61. These connections provide a discriminating circuit which per se is well known in the prior art and needs no description here. It will be noted, however, that voltages in phase opposition are induced from circuit 47 onto circuit 50 and these voltages are applied in phase opposition to the diodes 60 and 61 and that these voltages change in phase with changes in the mean frequency of the energy in 47 and also with faster changes such as changes at syllabic and signal frequency. Voltages are also induced by coupling condenser in phase on the diodes 60 and 61. These latter voltages are 35 of substantially constant phase irrespective of changes in the wave length of the voltages at 47. In this manner changes in the wave length of the wave energy generated in circuit 13 are converted into linear amplitude changes in the discriminating circuit and the amplitude variations are rectified in diodes 60 and 61 and produce differential currents which set up potentials across the differentially connected resistors 64 and 66 which are fed by a timing network to 55 the control grid 31.

One side of the series resistances 64 and 66 is connected to ground and the other side is connected by resistor R1 and condenser C1 and resistor R2 and condenser C2 to the grid so that the potential on this grid is controlled in accordance with the modulation from 29 and also in accordance with potentials which are passed by rectifiers 60 and 61 and the network coupling the output of said rectifiers to grid 31.

In Fig. 1 of my above identified application the stabilizing potentials and degenerative potentials are both applied by a common time constant circuit from the rectifier outputs to the reactance tube control electrode. In Fig. 3 of my U. S. application, Ser. No. 312,446, filed January 5, 1940, Patent #2,279,660, dated April 14, 1942, separate connections between the rectifier output and different reactance tube control electrodes are provided, one for the stabilizing potentials and the other for the degeneration potentials.

It may be found desirable to separately control the functions of slow drift of the carrier frequency and the syllabic shift due to the unsymmetrical modulating wave or the shifts due to modulation where degeneration is to be used so that different amounts of control on the two functions may be used. This allows a very high degree of control on the slow response circuit which might cause motorboating if the speed of control is comparable to the syllabic frequency assuming for purposes of description that the second function is to control for non-symmetry of the modulation. Then a smaller amount of control may be used for the faster circuit which controls the syllabic shift. To do this the method and means of Fig. 3 of my United States application #312,446 filed January 5, 1940, Patent #2,279,660 may be used. In this arrangement the slow time constant controls one grid 28 of the reactance tube 10 and the fast control circuit controls the other grid 31. The fast control used in application 312,446 is, as pointed out above, normally fast enough for inverse feedback, but if this arrangement is used to correct for non-symmetry of modulation peaks as disclosed in my United States application #358,385, filed September 26, 1940, Patent #2,315,050, dated March 30, 1943, the time constant would be increased, that is made larger, to be comparable to the syllabic frequency.

The attached Fig. 1 shows another method by which a large value of slow control and a smaller value of faster control may be applied to a single grid of the reactance tube. In this arrangement the voltages derived from the differential output resistances 64 and 66 are impressed on a time constant circuit R1, C1. The voltages set up in R1 are also impressed from a tap on R1 to a second time control circuit R2, C2. Voltages unaffected by time control elements R1, C1 are supplied to R2 and timed by the elements R2, and C2, C1 in series and supplied to grid 31 of reactance tube 20. Voltages passed by the slower time constant circuit R1, C1 are also impressed by R2 on the grid 31 of tube 20. Since the time constant of units R2, C2 is shorter than the time constant of R1, C1, these latter voltages are not affected materially by R2, C2. Consequently, R1, C1 forms the slow time constant circuit which passes only very slow drifts. R2, C2 forms the faster time constant circuit which passes variations at a rate comparable to syllabic frequency, but with an amount which is somewhat smaller and is controlled by the slider on resistance R1.

The arrangement of Fig. 1 is similar to the

arrangement of Fig. 2 but differs therefrom in the following respects. In Fig. 2 a separate tube 70 has its electrodes coupled in oscillation generating circuits including a wave frequency stabilizing line 71 for the production of substantially constant frequency oscillations. These generated oscillations are fed by line 73 to diode rectifier 75 to mix or beat with the wave length modulated wave energy fed to said diode from the modulated generator 10 through line 36. The beat frequency output of 15, which for reasons pointed out in detail in my U. S. application, Ser. No. 136,578, Patent #2,279,659, mentioned above, is of substantially constant amplitude and is fed to the discriminator 41, 51, 50, etc. as in Fig. 1. In this discriminator all wave length variations are linearly converted into amplitude variations which are rectified in diode detectors 60 and 61 and appear across resistors 64 and 66. Voltage variations of a period higher than the modulation frequency are filtered by condensers 67 and 69 and the remaining potentials are fed to the capacity and resistance network R1—C1, R2—C2, and R3—C3, and thence to the suppressor grid 18 of the reactance tube along with modulation from transformer 29.

In Fig. 2, provision has been made to feed to the reactance tube potentials characteristic of slow drifts of the transmitter wave length, potentials characteristic of syllabic shifts thereof and potentials characteristic of changes thereof at modulation frequency, these latter potentials providing degeneration to improve the linearity of the modulated wave. The manner in which the slow drift control, syllabic shift control, and inverse feedback is fed to the reactance tube from the detectors 60 and 61 will now be described. R1—C1 and R2—C2 function the same as in Fig. 1, but R3—C3 is a time constant which is fast enough to pass all of the modulating frequencies so that inverse feedback takes place. The degree of inverse feedback is controllable by the variation of the sliders on R2 and R1 while the degree of control in accordance with potentials of syllabic rate is controllable by movement of the slider on R1. The operation of this means otherwise is as in Fig. 1 and further description thereof is believed unnecessary.

What is claimed is:

50. 1. In a signalling system, a tuned circuit wherein wave energy the wave length of which is to be controlled flows, a reactance tube coupled to said tuned circuit to control the tuning thereof and thereby control the wave length of the wave energy flowing therein, connections for modulating the conductivity of said reactance tube in accordance with signals to correspondingly control the wave length of the wave energy, a frequency responsive circuit for deriving potentials 55 characteristic of slow changes, and of syllabic changes, in the wave length of the wave energy, a resistance and a capacity in series, a second resistance and capacity in series connected across a part at least of said first resistance, connections 60 characteristic of slow changes, and of syllabic changes, in the wave length of the wave energy, a resistance and a capacity in series, a second resistance and capacity in series connected across a part at least of said first resistance, connections 65 from said first series resistance and capacity to said frequency responsive circuit for applying said derived potentials across said first series resistance and capacity, and connections between said second resistance and first capacity and said reactance tube.

2. In a signalling system, a tuned circuit wherein wave energy the wave length of which is to be controlled flows, a reactance tube coupled to said tuned circuit to control the tuning thereof and thereby control the wave length of the

wave energy flowing therein, connections for modulating the conductivity of said reactance tube in accordance with signals to correspondingly control the wave length of the wave energy, means for deriving potentials characteristic of slow changes, syllabic changes, and changes in accordance with signals in the wave length of the wave energy, and a resistive and capacitive network for applying said derived potentials to said reactance tube, said network comprising a first resistance and capacity in series, a second resistance and capacity in series connected to a part at least of said first resistance and a third capacity and resistance in series coupled to a part at least of said second resistance.

3. In a signalling system, a tuned circuit wherein wave energy the wave length of which is to be controlled flows, a reactance tube coupled to said tuned circuit to control the tuning thereof and thereby control the wave length of the wave energy flowing therein, connections for modulating the conductivity of said reactance tube in accordance with signals to correspondingly control the wave length of the wave energy, means for deriving potentials characteristic of slow changes, syllabic changes, and changes in accordance with signals in the wave length of the wave energy, and a resistive and capacitive network for simultaneously applying said derived potentials to said reactance tube.

4. In a signalling system, a tuned circuit wherein wave energy the wave length of which is to be controlled flows, a reactance tube coupled to said tuned circuit to control the tuning thereof and thereby control the wave length of the wave energy flowing therein, connections for modulating the conductivity of said reactance tube in accordance with signals to correspondingly control the wave length of the wave energy, means for deriving potentials characteristic of slow changes, syllabic changes, and changes in accordance with signals in the wave length of the wave energy, and an adjustable resistive and capacitive network for simultaneously applying said derived potentials to said reactance tube in separately controllable amounts.

5. Means for transferring potentials the frequencies of which fall within a plurality of ranges from one point to another including, a first resistance and condenser in a circuit excited by said potentials, said first resistance and condenser having a long time constant to pass variations of low frequency, an additional resistance and condenser in series in shunt to a part at least of said first resistance, to be excited by potentials of lesser amplitude, said additional resistance and condenser having a shorter time constant to pass variations of a frequency above the frequency of those passed by said first resistance and condenser, and an output coupled to said additional resistance and said first condenser.

6. Means for transferring potentials the frequencies of which fall within a plurality of ranges from one point to another including, a first resistance and condenser in a circuit excited by said potentials, said first resistance and condenser having a long time constant to pass variations of low frequency, an additional resistance and condenser in series in shunt to a part at least of said first resistance to be excited by potentials of lesser amplitude, said additional resistance and condenser having a shorter time constant to pass variations of a frequency above the frequency of those passed by said first resistance and con-

denser, a third resistance and condenser in shunt to a part at least of said second resistance to be excited by potential of amplitudes smaller than the amplitude of the potentials exciting said additional condenser and resistance, said third resistance and condenser having a time constant shorter than the time constant of said additional resistance and condenser to pass variations of a frequency above those passed by said additional resistance and condenser, and an output coupled to said third resistance and said first condenser.

5 7. In an angular velocity modulation system a network for transferring, from one point to another, potentials the frequency of which fall within a plurality of ranges, a first resistance and condenser in a circuit excited by said potentials, said first resistance and first condenser forming a time constant network of relatively long duration, a second resistance and second condenser in series in shunt to a part at least of said first resistance, said second resistance and second condenser forming a second time constant network of less duration than said first network and an output coupled to said second resistance and first condenser.

15 8. In an angular velocity modulation system a network for transferring, from one point to another, potentials the frequency of which fall within a plurality of ranges, a first resistance and condenser in a circuit excited by said potentials, said first resistance and first condenser forming a time constant network of relatively long duration, a second resistance and second condenser in series in shunt to a part at least of said first resistance, said second resistance and second condenser forming a second time constant network of less duration than said first network, a third resistance and condenser in shunt to a part at least of said second resistance, said third resistance and third condenser forming a third time constant network of less duration than said second network and an output coupled to said third resistance and first condenser.

25 9. In an angular velocity modulation system a network for transferring, from one point to another, potentials characteristic of slow changes in the frequency of a modulated carrier wave and characteristic of changes in the frequency of said carrier wave at syllabic frequency, a first resistance and condenser in a circuit excited by said potentials, said first resistance and first condenser forming a time constant network of a time duration appropriate for said slow changes, a second resistance and second condenser in series in shunt to a part at least of said first resistance, said second resistance and second condenser forming a time constant network appropriate for said syllabic changes, and output connections to said second resistance and first condenser.

30 10. In an angular velocity modulation system a network for transferring, from one point to another, potentials characteristic of slow changes in the frequency of a modulated carrier wave and characteristic of changes in the frequency of said carrier wave at syllabic frequency and modulation frequency, a first resistance and condenser in a circuit excited by said potentials, said first resistance and first condenser forming a time constant network of a time duration appropriate for said slow changes, a second resistance and second condenser in series in shunt to a part at least of said first resistance, said second resistance and second condenser forming a time constant network appropriate for said syllabic

changes, a third resistance and third condenser in series in shunt to a part at least of said second resistance, said third resistance and third condenser forming a time constant network appropriate for said modulation frequency and output connections to said third resistance and first condenser.

11. A system as recited in claim 9, wherein said resistances are adjustable.

12. In a network for transferring, from one point to another, potentials characteristic of slow changes in the frequency of a modulated carrier wave and characteristic of changes in the frequency of said carrier wave at syllabic frequency due to modulation thereof in a carrier stabilized timing modulation system of the reactance tube type, a first resistance and condenser in a circuit excited by said potentials, said first resistance and first condenser forming a time constant network of a time duration appropriate for said slow changes, a second resistance and second condenser in series in shunt to a part at least of said first resistance, said second resistance and second condenser forming a time constant network appropriate for said syllabic changes, and connections for coupling said second resistance and first condenser to electrodes of said reactance tube.

13. In a network for transferring, from one point to another, potentials characteristic of slow changes in the frequency of a modulated carrier wave and characteristic of changes in the frequency of said carrier wave at syllabic frequency due to modulation thereof in a carrier stabilized timing modulation system of the reactance tube type, a first resistance and condenser in a circuit excited by said potentials, said first resistance and first condenser forming a time constant network of a time duration appropriate for said slow changes, a second resistance and second condenser in series in shunt to a part at least of said

first resistance, said second resistance and second condenser forming a time constant network appropriate for said syllabic changes, a third resistance and a third condenser in series in shunt to a part at least of said second resistance, said third resistance and third condenser forming a time constant network appropriate for said modulation frequency and connections for coupling said third resistance and first condenser to electrodes of said reactance tube.

14. In a signalling system, a tuned circuit wherein wave energy the wave length of which is to be controlled flows, a reactance tube coupled to said tuned circuit to control the tuning thereof and thereby control the wave length of the wave energy flowing therein, connections for modulating the conductivity of said reactance tube in accordance with signals to correspondingly control the wave length of the wave energy, means for deriving potentials characteristic of slow changes, and syllabic changes, and a resistive and capacitive network for simultaneously applying said derived potentials to said reactance tube.

15. In a signalling system, a tuned circuit wherein wave energy the wave length of which is to be controlled flows, a reactance tube coupled to said tuned circuit to control the tuning thereof and thereby control the wave length of the wave energy flowing therein, connections for modulating the conductivity of said reactance tube in accordance with signals to correspondingly control the wave length of the wave energy, means for deriving potentials characteristic of slow changes and syllabic changes, and an adjustable resistive and capacitive network for simultaneously applying said derived potentials to said reactance tube in separately controllable amounts.
